UNITED STATES PATENT OFFICE.

ELIJAH T. SLAUGHTER, OF KANSAS CITY, MISSOURI.

AIR-HEATER.

No. 841,591.

Specification of Letters Patent.

Patented Jan. 15, 1907.

Application filed May 3, 1906. Serial No. 315,067.

To all whom it may concern:

Be it known that I, ELIJAH T. SLAUGHTER, a citizen of the United States, and a resident of Kansas City, in the county of Jackson and 5 State of Missouri, have invented an Improved Air-Heater, of which the following is a specification.

My invention is an improvement in that class of air-heaters in which cold or relatively 10 cool air is passed over or through a drum or other form of casing heated by a gas or other burner, the air escaping in a heated condition into the room in which the heater is located or into a pipe leading therefrom to another 15 room.

The chief objects obtained by my invention are greater simplicity and economy of construction of the heater and greater efficiency in the utilization of heat.

20 The details of construction, arrangement, and operation of the heater are illustrated in the accompanying drawings, in which—

Figure 1 is a central vertical section of the same. Fig. 2 is a transverse section on the 25 line 2 2 of Fig. 1. Fig. 3 is a transverse section on the line 3 3 of Fig. 1.

1 indicates the inner drum or shell, constituting the air-heater proper, 2 a drum or shell inclosing the inner drum 1, and 3 a casing surrounding and inclosing the top of the drums 1 and 2. All the parts 1 2 3 are arranged concentrically and spaced apart, as shown. The casing 3 and middle drum 2 are attached to and supported on a flat base 4.

30 The inner drum or air-heater proper, 1, is suspended from and supported by the middle drum 2 by means of a double-flange annulus or ring 5, the same being riveted to both, as will be readily understood from the drawings.

The air-heater 1 is made of less length than the drum 2, so that a large space is left below it to accommodate the gas or oil burner 6. The bottom 1^a of the air-heater 1 is cup 45 shape or concavo-convex in form and riveted to the lower end of part 1. This bottom 1^a is provided with a downwardly and laterally extended pipe 1^b, the same being preferably cast integral with the bottom. It extends 50 through the middle drum 2, and its mouth is adjacent to a large air-inlet 7, formed in the casing 3 near the bottom or base 4. The pipe 1^b is made of large capacity in order that cold or relatively cool air may be freely admitted into the chamber of the drum 1. The 55 top of the latter is open, but is traversed by a

pipe 8, which conveys the products of combustion across it. Both ends of this pipe terminate in the annular space that intervenes the inner and middle drums 1 2. The 60 latter is provided on one side, near the top, with a collar or short pipe 9, that extends into the conduit 10, which serves to convey off the products of combustion.

It will be seen in Fig. 1 that the pipe 8 terminates short of the pipe 9, or, in other words, a narrow space intervenes them. It is apparent that by the medium of the burner 6 the air entering the chamber of the drum 1 is heated not only by contact with 65 the cup-shape bottom 1^a, but also with the sides of the drum 1, with which the products of combustion circulate in contact, and also by the pipe 8, through which the products of combustion pass from one side to the 70 other of the air-heater 1.

It is obvious that if the pipe 8 extended into the short pipe 9, attached to the middle drum 2 and fitted therein, all the products of combustion would pass up the left-hand side 75 of the air-heater 1 and through the pipe 8, and in consequence the right-hand side of the part 1 would be heated to a less degree; but by arranging the pipe 8 so that a space is left between it and the escape-pipe 9 a current of 80 the products of combustion is induced on the right-hand side of the drum 1, and thus the circulation of the products of combustion and the heating of the drum 1 are equalized or rendered uniform.

The angle at which the air-inlet pipe 1^b is placed insures acceleration of the air-current as it passes into the chamber of drum 1 and also the efficient heating of the air by contact with the cup-shape bottom 1^a. By casting 85 the parts 1^a and 1^b integral a considerable economy is effected in the construction of the drum or air-heater proper.

It will be further seen that since the air-inlet pipe 1^b stops with the drum 2, or, in other 90 words, does not extend across the space between drums 2 and 3, a current of air may pass upward in the space between pipe 1^b and opening 7, so that there is no dead-air space at that point. Further, the air being freely 95 admitted at 7 may circulate around the lower portion of drum 2, and thus pass upward on the opposite side of the latter, as indicated by arrows. The top of the casing 3 is provided with openings through which the 100 heated air may pass into the room or apartment in which the heater is located. One of

such openings may be provided with a pipe 11, extended upward to any other room or apartment which requires to be heated, and another opening may be closed by a damper 5 12. Thus the escape of heated air from the heater may be regulated as required. Access may be had to the space in which the burner is located through a hinged or other door 13.

10 What I claim is—

1. The improved heater comprising the outer shell or casing having an air-inlet at the bottom and air-outlets at the top, the inner drum or air-heater proper, the middle drum 15 from which the air-heater is suspended, these parts being concentric and spaced apart, and the air-heater suspended from the middle drum and made of less length than the latter and provided with a cup-shape bottom having an air-inlet pipe extended downward and laterally through the middle drum and communicating with the air-inlet of the casing whereby air may enter the air-heater proper and also the annular space between 20 the casing and the middle drum, and a pipe for conveying the products of combustion arranged in the upper portion of the air-heater proper and its discharge end located 25 adjacent to but separated from the pipe conveying off the products of combustion whereby an induced current of the products of combustion is formed, substantially as described.

2. In an air-heater, a drum and a base to which it is attached, an inner drum or air-heater proper, and means for suspending it 35 from the inclosing drum, the bottom of said air-heater being cup shape and provided with a downwardly and laterally extended air-combustion, the same arranged in and 40 traversing the top portion of the air-heater, the outer drum having an alined pipe for conveying off the products of combustion, the two pipes being separated by a space as and for the purpose specified. 45

3. In an air-heater the combination with an inclosing drum 2 having a lateral pipe for conveyance of the products of combustion, of an inner drum or air-heater proper which is spaced from such outer drum, and means for 50 closing the space at the top and suspending the inner drum, the latter having a bottom provided with a downwardly-extended air-inlet, a pipe for conveying the products of combustion which is arranged in and traverses the upper portion of the air-heating drum, its discharging end being separated from the pipe conveying off the products of combustion from the outer drum, as described. 55
